UNITED STATES PATENT OFFICE.

MYRON CLAUS, OF RUSHFORD, NEW YORK.

HARNESS-FASTENER.

SPECIFICATION forming part of Letters Patent No. 255,416, dated March 28, 1882.

Application filed January 20, 1882. (No model.)

To all whom it may concern:

Be it known that I, MYRON CLAUS, a citizen of the United States, residing at Rushford, in the county of Allegany and State of New York, have made certain Improvements 5 in Adjustable Metallic Harness-Fasteners, of which the following is a specification.

This invention relates to an improved fastening device or lock to take the place of buckles, &c., used for fastening straps on harness, or other purposes, especially for fastening return-straps on harness that pass through a ring or D, and is usually to be covered by a sliding loop; and the invention consists in its construction and application, as hereinafter fully explained.

In the drawings, Figure 1 is a side elevation, partly in section; Fig. 2, a detail, full size, of the metal fastening separate from the straps. 20 A represents the fastening, made of a single piece of metal narrow in form, of sufficient size to go easily into the usual buckle-tongue holes in straps, &c. It is made into a fastener, as shown, by first being bent back at the top a short 25 distance, making a catch or hook, a, leaving a horizontal base part, b, which comes against the under side of a strap, B, with the hook a through the hole in said strap. For a short distance this part b is bent down straight, as 30 at b', for a space a little more than the usual thickness of a strap of ordinary size. It is then bent straight back, making a pointed shank or base, c, as shown, which comes closely against the under side of the second strap,

35 B', or return-strap, as shown in Fig. 1, in connection with a ring, D. It will be seen that the strap B pulls against the hook a, and the strap part B' pulls against the part b' of

the fastener, and the stronger the pull the tighter does the hook or fastener hold. A 40 sliding loop, C, (shown in dotted lines, Fig. 1,) slides on the two straps and covers the whole, including the fastener A. The loop C is made, if necessary, with a groove in the upper or lower inner surface to allow the ends of the 45 fastener to slide therein without friction.

The advantages of this fastener are that it is easily and quickly adjusted, it does not and cannot detach from the harness until removed by hand, there is no sewing or riveting it 50 on, and it is replaced, if lost, easily, being independent of a harness, and of small expense. It is easily adapted to many parts of a harness where any taking up or letting out is required. It has a double action, as it can 55 be inserted or taken out by the hook part a or other end, c. It is removed at either end instantly. Any weight or pull on the harness closes both ends a and c all the more tightly against its connecting straps, preventing 60 unfastening, even without a loop, C.

I claim—

The strap fastener A, consisting of a narrow piece of metal bent at the top to form the hook a, and provided with a longitudinal base, b, 65 the straight downwardly-bent portion b', and the supplemental longitudinal base c, in combination with the loop C, and adapted for use with the strap, substantially as specified.

In witness whereof I have hereunto signed 70 my name in the presence of two subscribing witnesses.

MYRON CLAUS.
